(57) **CLAIM**

The ornamental design for a drainage component, as shown and described.

DESCRIPTION

FIG. 1 is a perspective view of a first embodiment of a drainage component showing our new design;

FIG. 2 is a front view thereof;

FIG. 3 is a rear side view thereof;

FIG. 4 is a first side view thereof;

FIG. 5 is a second side view thereof;

FIG. 6 is a top view thereof;

FIG. 7 is a bottom view thereof;

FIG. 8 is a perspective view of a second embodiment of a drainage component showing our new design;

FIG. 9 is a front view of FIG. 8;

FIG. 10 is a rear view of FIG. 8;

FIG. 11 is a first side view of FIG. 8;

FIG. 12 is a second side view of FIG. 8;

FIG. 13 is a top view of FIG. 8; and,

FIG. 14 is a bottom view of FIG. 8.

The second embodiment of the drainage component is shown with a symbolic break in a length of the design, the symbolic break indicated by dash-dot-dash lines and form no part of the claimed design. The appearance of any portion of the drainage component between the dash-dot-dash break lines forms no part of the claimed design.
